and Stephen Leslie Bailey,
by Assignment — 1921.

UNITED STATES PATENT OFFICE.

WILLIAM WILSON DOUGLAS AND STEPHEN LESLIE BAILEY, OF BRISTOL, ENGLAND.

VALVE-OPERATING MECHANISM FOR INTERNAL-COMBUSTION ENGINES.

1,399,941.

Specification of Letters Patent. Patented Dec. 13, 1921.

Application filed May 12, 1919. Serial No. 296,366.

To all whom it may concern:

Be it known that we, WILLIAM WILSON DOUGLAS and STEPHEN LESLIE BAILEY, subjects of the King of England, residing at 5 Bristol, in the county of Gloucester, England, have invented certain new and useful Improvements in Valve-Operating Mechanism for Internal-Combustion Engines, of which the following is a specification.

- 10 This invention is for improvements in valve-operating mechanism for internal combustion engines and the like of the opposed twin-cylinder type, in which a single cam operates alternately valves in each of 15 the opposed cylinders. Usually one cam is provided for the inlet-valves and another cam for the exhaust-valves and a rocker is employed between each valve tappet and its operating cam.
- 20 The object of the invention is to provide a simple and symmetrical system permitting of both cylinders being alike with uniform timing of both valves.

In the accompanying drawings,—

- 25 Figure 1 is a horizontal section showing part of an engine to which this invention has been applied, and

Fig. 2 is a side elevation of the same with one cylinder removed.

- 30 Like letters indicate like parts throughout the drawings.

These show a horizontal opposed twin-cylinder engine of known type, wherein the exhaust valve stem A and tappet A² 35 of the one cylinder Y is parallel to, but not coaxial with, the corresponding exhaust valve stem B and tappet B² of the other cylinder Z. In this case a vertical cam-shaft C is employed, the axis of which is 40 situated so that the center lines of the tappets A² and B² are offset in the horizontal plane at equal distances on either side of it, as will be clearly seen. The rockers D, which are of known construction, swing in a 45 horizontal plane about vertical pivots D², which are situated alike with reference to the adjacent valve-tappets and the axis of the cam shaft. It is important that the rockers be similarly disposed relatively to

the direction of the rotation of the cam, 50 so that the valve lift diagrams of both valves may be the same.

The cam-shaft C and rockers are carried (the former in bearings at J) upon a frame or plate E which is detachably mounted 55 upon the engine crankcase F so that it constitutes in itself a unit.

To provide for relieving the compression in known manner by raising the exhaust valves off their seatings, a supplementary cam R may be provided having swells on opposite sides. This cam is formed on a sleeve R² loosely mounted on the cam shaft C, and operatively connected to a hand-controlled plunger S by which it is normally 60 held stationary by the spring T with its cam swells inoperative. On moving the plunger S to the left in Fig. 2 the two cam swells are brought into contact with the two exhaust-valve rockers D, which are made sufficiently wide for this purpose, and thus 65 the two exhaust-valves are simultaneously lifted.

The inlet-valves (one of which is shown 70 at O) are operated by a cam N and rockers M arranged similarly to those employed for the exhaust-valves. The cam-shaft C may be extended and provided with gearing at L to operate the shaft K which may operate a magneto or any other device.

In an engine of the opposed cylinder type the cylinder axes are generally out of line with one another. Preferably the amount of this offset in this case is the same as that of the two valve stems in relation 85 to one another, so that the distance of each valve stem from its cylinder axis is the same in both cases and the cylinders complete may be interchangeable.

What we claim as our invention and desire to secure by Letters Patent is:—

1. In an internal combustion engine of the twin type the combination with a pair of opposed cylinders offset relative to each other, of a single cam shaft, an inlet and 95 an exhaust valve for each cylinder, a pair of tappets for the two inlet and the two exhaust valves, the tappets of each pair being

offset relative to each other in the same relationship as the two cylinders, a single cam provided on said cam shaft for each pair of tappets, and a pair of rockers provided 5 for each pair of tappets and arranged symmetrically on opposite sides of the axis of said cam extending in opposite directions.

2. The combination as set forth in claim 1 including the engine crank casing and a 10 plate detachably mounted on said casing and carrying the cam-shaft and the oppo-

sitely extending rockers, forming a unit, and bearings on said plate for said cam-shaft.

In testimony whereof we have signed our names to this specification in the presence 15 of two subscribing witnesses.

WILLIAM WILSON DOUGLAS.
STEPHEN LESLIE BAILEY.
